UNITED STATES PATENT OFFICE.

CHARLES REINEKE, OF NEW YORK, N. Y., ASSIGNOR TO THE REINEKE MOTOR CORPORATION, OF NEW YORK, N. Y., A CORPORATION OF DELAWARE.

ENGINE.

Application filed July 19, 1919, Serial No. 311,976. Renewed May 12, 1926.

This invention relates to certain new and useful improvements in engines, and contemplates more especially an internal combustion engine primarily designed for marine propulsion.

An object of this invention is the production of an engine having a relatively high speed multi-stroke piston travel designed to impart to a main or power shaft a comparatively slower speed of rotation with resulting maximum efficiency.

Another object of the present invention is to produce a high speed internal combustion type of engine in which two or more strokes of the piston are obtained for every revolution of the power shaft, thereby obtaining a direct reduction of the power for heavy duty without the interposition of various forms of reduction gear and similar devices.

A further object of this invention is the production of a comparatively simple and durably constructed engine possessing advantages of assembly, and relatively low in cost of manufacture.

With these and other objects in view the invention further consists in the arrangement and construction of the several parts hereinafter described and pointed out in the appended claims.

In the accompanying drawings which illustrate certain embodiments of my invention and in which similar reference characters designate corresponding parts,

Fig. 1 is a vertical sectional view through my improved engine illustrating two cylinders and the relative position of the pistons therein;

Fig. 2 is a transverse vertical sectional view showing the opposed pistons in firing position, and the several interconnected parts in their respective associations therewith;

Fig. 3 is a similar view to Fig. 2, illustrating the opposed pistons in an extreme outward position, and the several associated parts relatively positioned therewith;

Fig. 4 is a detail, sectional view showing the respective frame sections of the opposed pistons in associated position;

Fig. 5 is a detail, sectional view of the upper frame section interconnected with the lowermost piston;

Fig. 6 is a detail, sectional view illustrating the frame section interconnected with the uppermost piston;

Fig. 7 is a horizontal, sectional view through the crank case illustrating the respective frames sections interconnected with the crank element of the power shaft;

Fig. 8 is a top plan view of the engine shown in Fig. 1, with parts broken away.

The present invention has been primarily designed for use in marine propulsion, but it will be understood that it is equally applicable to other power uses of a stationary or mobile type. It will be further understood that while I have shown and principally described an internal explosive type of engine, that the utilization of steam, oil, compressed air and other power mediums may be employed and such variations in design made in the engine as will permit of their use without departing from the spirit of my invention.

Referring to the drawings, the invention comprises among other things a vertically arranged cylinder in which is reciprocally mounted in opposed relation two pistons, and a novel means of transmitting the movement of said pistons to a power shaft, whereby two or more power strokes of the pistons are obtained for every revolution of the shaft. The fuel charge is designed to be admitted between the opposed pistons and fired by compression or any suitable ignition device.

The power transmitting mechanism is interconnected with the opposed pistons and the power shaft and comprises a rotatable member of crank like formation which can be designed to receive a succession of power strokes for every revolution of the power shaft to which the rotatable member is attached. A compensating device is also provided for use in stabilizing the uniform co-operation of the opposed pistons.

Reference being had particularly to Figs. 1 to 8 inclusive, my improved multi-stroke engine includes a crank case 1 formed of a base section 2 and an intermediate section 3, upon which latter are formed the cylinders 4. There may be a single, or other multiples of cylinders used, but for purposes of illustration herein I have shown two.

The several co-operating parts of each

cylinder being the same, the same reference characters will apply to each and I shall describe but one cylinder and its associated elements in detail.

5 Secured to the cylinders 4 is a top or cap section 5 suitably bolted thereto as shown at 6 in Fig. 8. The crank case 1 is provided with the usual bearings 7 and 8 in which is supported the main or power shaft 9 provided
10 with a fly wheel 10. The shaft 9 may be coupled to any suitable device for imparting motion thereto, such for example, as the propeller of a ship.

The main shaft 9 is provided with a crank element 11, which comprises a plurality of discs or similar supporting members 12 and 13, between which are mounted rollers 14 in diametrical relation. The rollers 14 are freely revoluble upon shafts 15 journaled in the disc members 12 and 13, and are designed to operate between movable frame sections 16 and 17 interconnected with the opposed pistons in a manner now to be described.

The respective frame sections 16 and 17 are vertically movable within the crank case 1 and are positioned therein as best illustrated in Fig. 7. Openings 18 are formed upon each side of the crank case into which the frame sections 16 and 17 are slidably positioned. Closure plates 19 are bolted as at 20 over their openings after the frame sections have been inserted. It will be seen that the sides of the opening 18 in the crank case, and the inner face of the closure plates 19 form suitable guides within which the frame sections may reciprocate. While I have shown this form of guide, it will be understood that various other types may be employed. I do not limit myself to the actual form set forth herein.

The upper frame section 16 is preferably secured as at 21 to a flange 22 of the lowermost piston 23, while the lower frame section 17 is connected to the uppermost piston 24, by means of connecting rods 25 secured at 26 to a depending sleeve portion 27 of the piston 24 to be hereinafter described.

The upper frame section 16 is shown in detail in Figs. 4 and 5, and comprises a web portion 28 formed with an upper flange 29 secured to the flange 22 of the lower piston, and a lower flange 30 designed to contact with the rollers 14 hereinbefore described. In cross-section this portion of the frame 16 just described is of I-beam formation, and extends transversely of the piston as will be understood. The opposite side walls 31 and 32 of the frame section 16 are grooved as at 33 to receive vertically extending bars 34 and 35 of the lower frame section 17 as will presently appear. Each side wall is further cut away as at 36 to permit the operation of the lower frame section 17 which co-operates with the aforesaid frame section 16.

65 A cross rib in the nature of a cam 37 ex-

tends between the wall 31 and 32 of the frame section 16 and is designed to co-operate with a series of rollers 38 carried by the disc member 13 for a purpose to be hereinafter described. Each side wall 31 and 32 of the frame section is further cut away as at 39 to receive portions of the lower frame section 17, see Figs. 4, 5 and 7.

The lower frame section 17 is shown in detail in Figs. 4 and 6, and comprises a relatively U-shaped member including the vertically extending bars 34 and 35, and a lower cross bar 40 designed to bear upon the rollers 14.

The bars 34 and 35 extend upwardly into the grooves 33 formed in the frame section 16, and are reduced to form the connecting rods 25 secured to the uppermost piston 24 hereinbefore referred to, as clearly shown in Fig. 3.

Extending from the frame section 17 are arms 41 adapted to slide in the cut-away portions 39 of the frame 16 hereinbefore described. Connecting the aforesaid arms 41 is a rib member 42 in the nature of a cam 90 designed to co-operate with a series of rollers 43 carried by the disc member 12 for a purpose to be now described in conjunction with the rib member 37 co-operating with rollers 38 hereinbefore referred to.

Referring to Figs. 2 and 3, the extreme positions of the frame sections 16 and 17 are illustrated, and as a result the respective rib members 37 and 42 thereof are shown in their positions with relation to the co-operating series of rollers 38 and 43, respectively.

Each rib member 37 and 42 is cam-like in construction, being provided with curved cut-away portions 44 and 45 respectively, terminating in intermediate projecting noses 46 and 47, respectively, against which latter the respective rollers 38 and 43 are designed to ride, and thereby regulate the relative positioning of the pistons 23 and 24. These members 37 and 42 are primarily provided to prevent the dropping of the pistons when the engine is not in use, it being apparent that if this or similar means were not provided the weight of the pistons and the interconnected parts would tend to unbalance the stroke and prevent the successful operation of the engine. In operation, the rollers 38 carried by the disc member 13 coact with the projecting nose 46 and the cut-away portion 45 of the rib member 37, and the rollers 43 carried by the disc member 12 coact with the projecting nose 47 and the cut-away portion 44 of the rib member 42.

The pistons 23 and 24 are positioned within the cylinder 4 in opposed relation, and are shown in their extreme positions in Figs. 1, 2 and 3. The lowermost piston 23 is provided with the flange 22 hereinbefore referred to as interconnected with the

frame section 16. A head 48 is also formed on the piston 23. The uppermost piston 24 is provided with a similar head 49 between which and the head 48 of the piston 23, the 5 fuel charge of the engine is compressed. Any suitable form of ignition device, such as a spark plug 50, may be used to explode the compressed charge.

A flange 51 is formed on the uppermost 10 piston 24 and is more especially designed to operate as a piston element within a cylinder 52 provided in the cap section 5 of the engine. The purpose of this piston element is to produce a sufficient quantity of compressed air to thoroughly scavenge the cylinder 4 after the working stroke of the engine, and to also store and direct a quantity of compressed air into the fuel supply pipe whereby the fuel may be injected or otherwise 15 accelerated in its passage to the explosion chamber formed between the pistons 23 and 24 in the cylinder 4. Suitable ports are provided in the piston 24, cylinder 4, and cap section 5, which, when in and out of register, permit of the operation of the engine 20 in a manner to be now described.

The cap section 5 is provided with an air inlet valve 53, which is normally seated by means of a spring 54. Upon a down stroke 30 of the piston 24 this valve is unseated and a quantity of air drawn in through the openings 55.

The piston 24 is chambered as shown and is provided with a series of annularly arranged and superimposed ports 56 and 57, adapted to register at certain times with a similar arrangement of ports 58 and 59 formed in the cylinder 4.

In the position shown in Fig. 3, the ports 40 56 in the piston 24 are in register with the ports 59 of the cylinder 4. In Fig. 2 the several ports just described are shown out of register.

A series of exhaust ports 60 are provided 45 in the cylinder 4, through which the burnt gases of the previous explosions are scavenged or discharged by compressed air, through the action of the piston element 51 operating in the cylinder 52.

50 Referring to Fig. 2, the pistons 23 and 24 are in firing position. Upon the up stroke of the piston 24 carrying the piston element 51, it will be seen that the air drawn in through the valve 53 on the previous down stroke, will be compressed within the cylinder 52 and subsequently within the chambered portion of the said piston 24. As the piston 24 reaches its uppermost position the ports 56 in the piston register with 55 the ports 59 in the cylinder and the compressed charge of air is allowed to escape through said ports into a communicating chamber 61 from where it passes through the ports 58 into the firing chamber of the 60 engine between the pistons 23 and 24. The

burnt gases remaining therein are forced out by the compressed air through the exhaust ports 60 as will be understood.

A portion of the compressed air is also allowed to escape from the chambered portion 70 of the piston 24, through the ports 57 into that annular portion indicated at 62 in Fig. 3, of the cylinder 52 formed between the lower face of the flange on piston element 51 and the top of the cylinder 4. This 75 portion of the air is further compressed upon the down stroke of the piston 24 and finally discharged through a port 63 formed in the depending sleeve portion 27 hereinbefore referred to of the piston 24, and a 80 registering port 64 formed in the cylinder 4 into a pipe 65 leading to the fuel supply conduit or pipe 66. A check valve 67 is located within the pipe 65. The foregoing construction is disclosed in Fig. 2 of the 85 drawings and may be used to accelerate the introduction of the fuel into the cylinder 4, upon the principle of an injector or similar fuel device, the construction of which may be of any standard type. 90

In operation, the explosive charge is fired between the opposed pistons 23 and 24, which as they separate, impart a direct movement to the crank-like element composed of the discs 12 and 13 and rollers 14. 95 This movement is imparted through the connections of the respective frame sections 16 and 17 hereinbefore referred to, and particularly through the connecting rods 25 of the lower frame 17 and the I-beam construction 100 of the upper frame 16, both of which connections are directly connected to the respective pistons 24 and 23.

The working stroke of the pistons 23 and 24 imparts a quarter turn or movement to 105 the crank element as best illustrated in the two positions shown in Figs. 2 and 3. Upon the return stroke of the pistons 23 and 24 the crank element makes another quarter turn as will be understood. It will be seen 110 therefore, that for each complete stroke or cycle of the pistons, a half revolution is imparted to the power shaft 9 through the crank elements and the several interconnected parts. 115

A second complete stroke or cycle of the pistons 23 and 24 will therefore produce a complete or single revolution of the main or power shaft 9.

By this construction it will be apparent 120 that for every complete revolution of the power or main shaft 9, two complete strokes or complete cycles of the pistons 23 and 24 are necessary. In like manner a greater number of strokes or complete cycles of the 125 pistons can be obtained by interposing a greater number of rollers 14 in the crank element, or otherwise camming the said crank element according to the work to be done.

In the preferred form, the rollers 14 are 130

movable with the disc members 12 and 13 between the frame sections 16 and 17 as clearly shown in Fig. 3. Upon each reciprocation of the pistons 23 and 24 their frame sections are likewise reciprocated, thereby imparting a direct movement to the rollers 14 in a circular movement about the main or power shaft 9 as will be understood. The compensating or stabilizing series of rollers 10 38 and 43 respectively also carried by the disc members 12 and 13 are free to revolve in the cam-like rib members 37 and 42 as has been heretofore described.

It has heretofore been proposed to drive a 15 shaft by a plurality of engines, each engine having its own power shaft, and speed reducing gear being arranged between the power shafts and the driven shaft. In contradistinction to a construction of this character, 20 it will be noted in my engine that the power is transmitted directly from the opposed pistons to the power shaft of the engine at the rate of a plurality of power strokes of the pistons to each revolution of the power shaft.

25 From the foregoing it will be obvious, that I have produced an efficient engine wherein a maximum power revolution of the main shaft can be obtained through the multiplicity of predetermined power strokes of an 30 engine piston irrespective of the fuel medium employed.

Various changes in the form and arrangement of the several parts may be made without departing from the spirit of my invention and I do not limit myself to the exact 35 forms set forth herein.

I claim:

1. In combination, an engine having a rotating shaft, projections fixed to said shaft, 40 a cylinder, opposed pistons arranged in said cylinder, means connected to said pistons and engaging one of said projections for imparting power strokes direct to the projection at the rate of a plurality of power 45 strokes of the pistons to each revolution of the shaft, and means connected to the pistons and engaging another one of said projections for driving the pistons on the idle strokes.

50 2. In a multi-stroke engine, the combination with a cylinder having opposed pistons arranged therein, a power shaft arranged beyond one end of the portion of the bore of the cylinder in which the pistons move, members actuated by said pistons, and means carried by said power shaft and co-acting with said members for causing a multiplicity of power strokes of the pistons to impart a single revolution only to the power shaft, said 55 means being rotatable with said power shaft in a single direction only.

60 3. In a multi-stroke engine, the combination with a cylinder having opposed pistons arranged therein, a power shaft arranged beyond one end of the portion of the bore of

the cylinder in which the pistons move, opposed cranks for said shaft, said cranks being operable in the same direction as the shaft, and means operatively interconnecting said pistons and cranks for causing a multiplicity of power strokes of said pistons to impart a single revolution only to said power shaft.

4. In a multi-stroke engine, the combination with a cylinder having opposed pistons arranged therein, a power shaft arranged beyond one end of the portion of the bore of the cylinder in which the pistons move, diametrically opposite cranks for said shaft, and means operatively connecting the pistons and cranks for causing a multiplicity of power strokes of the pistons to impart a single revolution only to said shaft.

5. An engine of the class described including in combination a cylinder, opposed pistons arranged in said cylinder, a power shaft, a crank element rotatable with said shaft in one direction, means including movable frame sections connected to said pistons, and a series of rollers arranged on said crank element and engaging said frame sections for causing a multiplicity of power strokes of the pistons to be imparted to the power shaft for every revolution thereof during a single revolution of said crank element.

6. An engine of the class described including in combination a cylinder, opposed pistons arranged in said cylinder, a power shaft, a crank element for said shaft consisting of a pair of spaced disks having spaced rollers actuated by the pistons and mounted between the disks on axes parallel with the axis of the shaft, said rollers functioning to move the pistons toward each other, other rollers arranged on the outer sides of the disks for moving the pistons away from each other, and means including frame sections connected to said pistons and arranged on opposite sides of the last mentioned rollers of the crank element, the parts being arranged to cause a multiplicity of power strokes of pistons to impart a single revolution only to said shaft.

7. An engine of the class described including in combination a cylinder, opposed pistons arranged therein, a power transmitting element for each piston, a power shaft, a crank element for each of said power transmitting members carried by said shaft, each of said crank elements being engageable with its corresponding power transmitting element during a portion of the stroke of the pistons and disengageable from its corresponding power transmission member during the remainder of said stroke, said crank elements being adapted to rotate with said shaft in a single direction, said power transmitting elements including movable frame members interconnected with said pistons and crank elements for imparting a multiplicity of

power strokes of the pistons to the power shaft for every revolution thereof and during a single revolution of said crank elements, and means for guiding said frame members.

5 8. An engine of the class described including in combination a cylinder, opposed pistons arranged therein, a power shaft and crank elements carried thereby, said crank elements being adapted to rotate with said shaft in a single direction, movable frame members interconnected with said pistons and engine with a crank element during a portion of the stroke of said pistons and disengageable from the same crank element during the remainder of the same stroke for causing a multiplicity of power strokes of the pistons to be imparted to said power shaft for every revolution thereof and during a single revolution of said crank elements, guides for said frame members, and means carried by said guides for maintaining the said pistons in timed relation.

20 9. An engine of the class described including in combination a cylinder, opposed pistons arranged therein, a power shaft and crank elements carried thereby, said crank elements being rotatable in a single direction with said shaft, movable frame sections interconnected with said pistons and each engageable with a crank element during a portion of the stroke of the pistons and disengageable from the same crank element during the remainder of the same stroke for imparting a multiplicity of power strokes of the pistons to the power shaft for every revolution thereof and during a single revolution of said crank elements, means for guiding said frame members, and means for sustaining the movable frame sections in timed relation with the pistons of the engine.

25 10. In an engine of the class described including in combination a cylinder, opposed pistons arranged therein, a power shaft and crank elements carried thereby, said crank elements being rotatable in a single direction, movable frame sections interconnected with said pistons and each engageable with a crank element during a portion of the stroke of the pistons and disengageable from the same crank element during the remainder of the same stroke for imparting a multi-

plicity of power strokes of the pistons to the power shaft for every revolution thereof and during a single revolution of said crank elements, means for guiding said frame members, and means including a cam and roller for sustaining the movable frame sections in timed relation with the pistons of the engine.

55 11. An engine of the class described including in combination a cylinder, opposed pistons arranged therein, a power shaft and crank element carried thereby, movable frame sections interconnected with said pistons and crank element for imparting a multiplicity of strokes of the pistons to the power shaft for every revolution thereof, means for guiding said frame members, and means including cams carried by the aforesaid movable frame sections and a series of rollers positioned on the crank element for engagement with the said cams, whereby the movable frame sections are sustained in timed relation with the pistons of the engine.

60 12. In a multi-stroke engine, a cylinder, opposed pistons arranged in said cylinder and movable in said cylinder away from each other, a power shaft arranged beyond one end of the portion of the bore of the cylinder in which the pistons move and having its axis intersected by the axis of the cylinder, power transmitting elements connected to said pistons, and combined power receiving and transmitting members associated with said shaft and cooperating with said elements for causing a multiplicity of power strokes of the pistons to impart a single revolution only to said shaft.

65 13. An internal combustion engine including a cylinder, opposed pistons arranged in said cylinder, a shaft, projections on said shaft, thrust means on the pistons slidably engageable with one of said projections and adapted to move said projections with the shaft approximately 360 degrees about the axis of the shaft for each plurality of power strokes of the pistons, and means connected to the pistons and slidably engageable with another one of the projections on the shaft for driving the pistons on their idle strokes.

70 75 80 85 90 95 100 In testimony whereof I affix my signature.

CHARLES REINEKE.
